UNITED STATES PATENT OFFICE.

EDWARD A. HALBLEIB, OF ROCHESTER, NEW YORK, ASSIGNOR TO NORTH EAST ELECTRIC COMPANY, A CORPORATION OF NEW YORK.

GEARING.

1,087,288.

Specification of Letters Patent.

Patented Feb. 17, 1914.

Application filed April 5, 1913. Serial No. 759,253.

To all whom it may concern:

Be it known that I, EDWARD A. HALBLEIB, a citizen of the United States, and resident of Rochester, in the county of Monroe and 5 State of New York, have invented certain new and useful Improvements in Gearing, of which the following is a specification.

This invention relates to gearing such as is employed in connection with apparatus, 10 for starting an internal-combustion engine, wherein an electric machine or other prime-mover is employed alternatively as a motor to start the engine, and as a generator to store energy in a storage-battery or other device, 15 the gearing in question being employed to connect the prime-mover with the engine for both of these purposes.

In apparatus of the type in question it has been proposed to employ gearing in 20 which automatic clutches are embodied, such gearing operating at different speed ratios according as the prime-mover or the engine constitutes the source of power, so that the prime mover may be normally 25 driven at a comparatively low speed suitable for generating, while it may drive the engine through a higher gear ratio when acting as a motor. Such gearing, when entirely automatic in action, has the characteristic 30 that it tends to lock itself automatically against reverse movement. Accordingly, in a motor-vehicle equipped with starting-apparatus of the type in question, in case the engine comes to rest as, for example, by being stalled, while it is connected, through 35 the usual transmission-gearing, with the traction-wheels of the vehicle, and while the vehicle is moving up a sloping surface on which it tends to move backwardly when at 40 rest, the gearing of the starting-apparatus tends to resist such backward movement, through its connection with the traction-mechanism of the vehicle. Where the starting-mechanism is connected directly with a 45 rotating part of the engine this tendency is not a matter of consequence, for the reason that the disengagement of the usual driving-clutch acts to disconnect the starting-mechanism, as well as the engine, from the transmission-mechanism of the vehicle. In certain 50 cases, however, it is more convenient to connect the starting-mechanism to the driving-mechanism of the vehicle in the rear of the driving-clutch, and in such a case the 55 conditions above referred to cannot be re-

lieved by the release of the driving-clutch. In consequence of this fact the sliding-jaw clutch commonly employed in the transmission-mechanism of the vehicle may be subjected, under the circumstances in question, 60 to a torque by which it is rendered difficult or impossible to disengage its members by means of the usual hand-levers, as is necessary before the engine and the vehicle can be started again.

One object of the present invention is to provide an automatic gearing, for use in connection with engine-starting mechanism of the type in question, wherein provision is made for avoiding the objectionable condition just pointed out; and to this end I propose to employ means, in the nature of a clutch, embodied in the gearing and operative to disconnect its elements in such a manner as to avoid the automatic locking-action of the gearing. More particularly, I propose to actuate this clutch by connection with the means by which the usual driving-clutch of the vehicle is normally operated, so that the gear is unlocked without any attention or any additional movement on the part of the operator of the vehicle.

Other objects of the invention, and the features of construction by which they are attained, will be set forth in connection with 85 the following description of the illustrated embodiment of the invention.

In the drawings:—Figure 1 is a side-elevation showing, in vertical-section, a gearing embodying the present invention, and 90 illustrating, diagrammatically, certain parts of the power-mechanism of a motor-vehicle in connection with which it is employed; and Fig. 2 is a vertical section on the line 2—2 in Fig. 1, looking from left to right in 95 the latter figure.

The invention is illustrated as embodied in connection with a gearing constructed in accordance with my pending application, Serial No. 673,271, filed January 24, 1912. 100 In that application I disclosed a gearing in which the automatic action results from the use of roller-clutches, and in which frictional connections are employed to prevent the gearing from being locked positively against 105 reverse rotation in the event of a back-kick. In the present case, for convenience and simplicity in construction, I utilize such frictional connections also for the present purpose of unlocking the gearing to release the 110

transmission-mechanism of the vehicle, the frictional connections being in the form of a clutch which may be disengaged for this purpose.

- 5 In Fig. 1 a portion of the electric machine or motor-generator 5 is illustrated, together with the gearing 6 of a starting-mechanism, the engine 7 and the transmission-gearing 8 of the vehicle, and the driving-clutch 9 by 10 which the engine is connected with or disconnected from the transmission-gearing in the usual manner.

The armature-shaft 11 of the generator 5 is connected, by a coupling 12, with a shaft 13 constituting a part of the gearing by which the generator is connected with the engine, and this shaft is hereinafter referred to as the "secondary shaft." It is journaled in a casing 14, and is provided, near 20 its right-hand end, with an enlargement of which the periphery forms a clutch-element 15. This clutch-element, as shown in Fig. 2, has inclined pockets in which are supported spring-pressed friction rollers 16. 25 These rollers cooperate with a smooth internal surface on a shell 17, which constitutes the outer member of the clutch, and the operation of these parts is such that when the member 17 rotates in the direction of the arrow 30 in Fig. 2, the rollers grip against this member so as to drive the member 15, and the shaft 13, at the same speed as the member 17, and cause the electric machine to be actuated as a generator. The clutch-member 35 35 is integral with a shaft 18, also journaled in the casing 14 in line with the shafts 11 and 13, and this shaft 18 is provided with a sprocket-wheel 19 by which it may be connected, through a sprocket-chain, with a rotary-member or shaft connected with the engine. The shaft 18 is hereinafter designated as the "primary shaft."

To permit the electric machine to actuate the engine, for the purpose of starting the latter, at a greatly reduced speed-ratio, the shaft 13 is provided with an integral pinion 20, which meshes with a gear-wheel 21 rotatable about a shaft 22 mounted in the casing 14. This gear-wheel 21 is connected 45 with a pinion 23, which meshes with a gear-wheel 25 mounted to rotate concentrically with the clutch-member 17. As in my said application, the gear-wheel 25 is annular in form, and is supported, at its inner surface, 50 upon friction-rollers 26 resting in inclined pockets in the periphery of the clutch-member 17, as shown in Fig. 2. The operation of these parts is such that when the electric machine acts as a motor the pinion 20 drives 55 the gear 21, and the pinion 23 drives the gear 25, in the direction of the arrows applied to these parts in Fig. 2, and the friction-rollers 26 cause the clutch-member 17 to 60 be driven by, and at the same speed as, the gear 25, whereby the shaft 18 and the 65

sprocket 19 are driven by the electric machine, but at a lower speed of rotation than that of the armature-shaft, and the rotation of the sprocket-wheel is communicated, in turn, to the engine through the connections 70 provided for that purpose.

The frictional connections hereinbefore referred to are provided between the gear 21 and the pinion 23, as shown in Fig. 1. To this end the gear 21 has an annular rim 75 which is fastened, by screws 28, to a plate 27 journaled loosely, at its center, upon the shaft 22. The rim of the gear is provided with a conical clutch-surface 29, which is engaged by a corresponding surface on a clutch-member 30 integral with the pinion 23. The clutch-surface are normally pressed into engagement by the action of compression-springs 31 mounted loosely upon studs 32 fixed to the inner surface of 80 the plate 27. These springs press against a friction-plate 33, loosely mounted on the shaft 22 and engaging the inner surface of the clutch-member 30, whereby the conical clutch-surfaces are forced together by the 85 resulting axial movement of the parts upon the shaft 22.

The gearing, as so far described, is substantially the same in construction and operation as the gearing of my said application, and the present invention is embodied particularly in the combination, with the above-described parts, of means whereby the friction-clutch just described may be disengaged when necessary. To this end the shaft 22 is arranged to be movable longitudinally in its bearings in the casing 14, and a lever 46 is pivoted between lugs 48 fixed to the casing, as shown in Fig. 1. The upper end of this lever may engage the right-hand end of the shaft 22, so that when the lower end of the lever is swung outwardly the shaft is moved longitudinally, in a left-hand direction. The shaft is provided with a shoulder 49 which engages the right-hand surface of the friction-plate 33. Accordingly the longitudinal movement of the shaft causes this shoulder to press the friction-plate away from the clutch-member 30, thus relieving the clutch-members from the 95 pressure of the springs 31. In order that the clutch-members may be entirely free from each other the shaft 22 is provided also with a shoulder 50 adapted to engage a washer 51 adjacent the pinion 23, and the continued movement of the shaft causes the shoulder 50 and the washer 51 to force the pinion and the clutch-member 30 to the left, thus disengaging the clutch-member entirely 100 from the clutch-surface 29 on the gear 21. 105 When the friction-clutch is disengaged, as just described, the gearing no longer has any locking-action by which reverse rotation of the sprocket-wheel 19 may be prevented.

To illustrate the manner in which my im- 110

proved gearing is employed in connection with a motor-vehicle, and is automatically operated through the operation of the usual pedal, or other means, for disengaging the

5 driving-clutch of the vehicle, I have illustrated the lever 46 as connected, through a link 47, with the clutch-lever 36, which is journaled, in the usual manner upon a shaft or stud 37, and provided, at its upper end, 10 with a pedal 38. The lower end of the clutch-lever co-operates, in the usual manner, with the sliding clutch-cone 34, which is normally pressed into engagement with the corresponding clutch-surface on the fly- 15 wheel of the engine 7 by means of a spring 35. The sprocket-wheel 19 is indicated diagrammatically as connected, by a chain 41, with a sprocket-wheel 40 on the power-shaft 39 of the vehicle, and this power-shaft is 20 connected with the drive-shaft 42 of the vehicle by means of the usual transmission-mechanism 8. This mechanism is shown diagrammatically as comprising the usual jaw-clutch for direct driving between the 25 power-shaft and the drive-shaft, this clutch having a member 43 fixed to the drive-shaft, and a member 44 splined to the power-shaft and controlled by a manually-operable lever 45. It will be apparent that in case the 30 engine becomes stalled when driving the vehicle, through the jaw-clutch, upon rising ground, so that the vehicle, after coming to rest, tends to run backwardly, the tractive efforts of the wheels will be transmitted, 35 through the drive-shaft and the jaw-clutch, to the sprocket-wheel 40, the chain 41 and the sprocket-wheel 19, and will tend to cause reverse rotation in the gearing. This reverse rotation will be normally resisted 40 by the locking action of the gearing, owing to the operation of the unidirectional clutches therein, and the frictional connection afforded by the friction clutch embodied in the gearing is sufficient to substan- 45 tially resist such reverse movement, so that the members 43 and 44 of the jaw-clutch will be pressed firmly together, rendering it difficult or impossible to shift the member 44 out of co-operation with the member 43. In 50 such a case, however, if the pedal 38 be depressed to disconnect the driving-clutch 9, it acts at the same time, through the connections above described, to disconnect the friction-clutch in the gearing, whereupon 55 the sprocket-wheel 19 in the gearing may rotate backwardly freely, thus relieving the torque upon the jaw-clutch and permitting it to be operated.

My invention is not limited to the embodiment thereof hereinbefore described and illustrated in the accompanying draw-

ings, but may be embodied in various other forms within the nature of the invention as it is defined in the following claims.

I claim:—

1. Gearing having, in combination, a primary rotary member; a secondary rotary member; irreversible mechanism connecting said members, whereby they may drive each other at different speed ratios according as 70 one or the other constitutes the driver, said mechanism including a normally-operative clutch; and means for throwing the clutch out of operation to permit reverse rotation of one of said rotary members. 75

2. Gearing having, in combination, a primary rotary member; a secondary rotary member; irreversible mechanism connecting said members, whereby they may drive each other at different speed-ratios according as 80 one or the other constitutes the driver, said mechanism including a normally-operative spring-controlled clutch; and manually-operable means for throwing the clutch out of operation to permit reverse rotation of 85 one of said rotary members.

3. The combination, with a motor-generator, an engine, transmission-mechanism, a driving-clutch connecting the engine and the transmission-mechanism, and manually- 90 operable means for throwing said clutch out of operation; of irreversible gearing connecting the motor-generator with the transmission-mechanism, whereby the motor-generator may drive the transmission-mechanism or the transmission-mechanism may drive the motor-generator, at different speed-ratios according as one or the other constitutes the driver, said gearing including a normally-operative clutch; 100 and connections between the last-mentioned clutch and said manually-operable means, whereby said clutch may be thrown out of operation simultaneously with the driving-clutch. 105

4. The combination, with a motor-generator, an engine, transmission-mechanism, and a driving-clutch for connecting the engine and the transmission-mechanism; of gearing normally connecting the motor-generator and the transmission-mechanism and including a normally-operative clutch; and manually-operable means for throwing both of said clutches simultaneously out of operation, whereby the transmission-mechanism 110 may be disconnected from both the engine and the motor-generator. 115
